Attorney

UNITED STATES PATENT OFFICE.

ROBERT W. OLSON, OF BELOIT, WISCONSIN.

MICROMETER ATTACHMENT.

Application filed September 13, 1926. Serial No. 135,124.

My present invention has to do with micrometers, and contemplates the provision of an attachment designed to avoid many of the disadvantages of devices now in use for measuring accurately small internal slots, bores, and the like, the attachment being of such character that a finely developed sense of touch is not necessary in the operation thereof, and hence the attachment is as accurate in the hands of an unskilled mechanic as it is in the hands of a highly skilled craftsman.

Other objects and practical advantages of the invention will be fully understood from the following description and claims when the same are read in connection with the drawings, accompanying and forming part of this specification, in which:—

Figure 1 is a view in side elevation showing the attachment constituting the preferred embodiment of my invention as properly applied to a micrometer.

Figure 2 comprises disconnected perspectives, on enlarged scales, of parts of the attachment hereinafter explicitly referred to.

Similar numerals of reference designate corresponding parts in both views of the drawing.

I show in Figure 1 a conventional micrometer having a graduated barrel 1, and a thimble 2 for cooperation with the said barrel and also for the movement of the usual element designated by 3.

My attachment is fastened to one arm 4 of the usual U-shaped portion of the micrometer, and it will be noted that among other elements my attachment includes a bar 5, grooved longitudinally at 6 and apertured at 7 and formed integral with or fixed to an arm 8 which is provided with a teat 9 and is also provided with a U-shaped portion 10 which is designed to straddle the end of the arm 4 and be detachably fixed thereto through the medium of a set screw 11.

In addition to the bar 5 and the arm or bracket 8, the attachment comprises a sleeve 12 slidable on the bar 5 and designed to be adjustably fixed thereto through the medium of a set screw 13, and equipped with an apertured projection 14 for the reception of a rod 15 which is normally pressed toward the right through the medium of a spring 16 interposed between the projection 14 and an enlargement 17 on the rod 15.

In one side the sleeve 12 is provided with

a threaded aperture 18, Figure 2, to receive a headed screw 19 which is designed to rest in the longitudinal slot 20 in the rear portion 21 of a slidable member 22. The said slidable member 22 is provided with an arcuate scale 23 for cooperation with a swingable pointer 24 which is pivoted at 25 in the member 22 and is provided with a slotted arm 26. It will also be noted that the member 22 is equipped with an arm 27 of channel form at 28 and provided on its outer side adjacent to its end with a teat 29, the said teat 29 being designed to bear at a point opposite the aforementioned teat 9 incident to the taking of an inside measurement.

The forward portion of the member 22 is arranged in lapped relation to a member 30 and is held under yielding pressure against the side of the said member 30 by the resiliency of the arm 27; it being understood in this connection that the member 30 is slotted at 31 to receive the bar 5, and that the channel portion 28 of the resilient arm 27 is pivotally connected at 32 to the member 30. It will also be understood that the member 30 has a stud 33 movable in the groove 6 of the bar 5 and also has a lateral pin 34, which extends through an arcuate slot 34^x in the inner wall of the member 22 and is disposed in the slot of the arm on the pointer 24, whereby swinging movement of the pointer 24 will attend sliding movement of the member 22. The rod 15 is pivotally connected at 35 to the rear side of the member 30. From this it will be understood that the spring 16 will operate to yieldingly hold the member 30 against movement toward the left in Figure 1. Adjacent to its lower end the member 30 is provided with a teat 36 that is opposed to the forward end of the micrometer element 3. I prefer that the teat 36 be in the form of a screw threaded into the lower end portion of the member 30, and that the said teat 36 be provided with one or more minute apertures 37 so that the shank of the said screw may be expeditiously and easily threaded into and out of the member 30 as when it is desired to substitute a smaller or larger teat 36 for the one illustrated.

The slot or opening 31 in the member 30 is slightly larger than the bar 5 to permit of pivotal or swinging movement of the member 30 on the bar 5 in the direction of the length of said bar, the center of said movement of the member 30 on bar 5 being

the pivot connection 32 between the member 30 and the arm 27.

It will be manifest from the foregoing that my novel attachment is readily applicable to and removable from a conventional micrometer, and that when applied as shown in Figure 1, the attachment is susceptible of use with great facility.

The device as shown in Figure 1 is capable of taking inside measurements in thousandths of an inch from about eight-sixteenths of an inch upward, and manifestly the low limit of the device will be determined by the design and construction, and the smaller the size of the device, the measurements of which are to be taken, the more useful will my novel device be found.

In the operation of my improvement the screw 13 is loosened and the parts associated with the sleeve 12 are moved along the bar 5 to a position commensurate approximately with the size of the parts to be measured. The points or teats 9 and 29 are then disposed in the part to be measured, the screw 13 is then tightened and the thimble of the micrometer is screwed or turned until the pointer 24 is coincident with the line in the center of the arcuate scale 23, it being remembered in this connection that the member 22 is slidable and that movement of the member 30 will by the connection described bring about movement of the pointer 24, whereupon the size of the part being measured may be read on the barrel 1 of the micrometer.

It will be apparent from the foregoing that by virtue of its construction my improvement is accurate in the hands of an unskilled workman which is manifestly an important advantage.

It will also be appreciated from the foregoing that my improvement is simple and inexpensive in construction, and is free of delicate parts such as are likely to get out of order after a short period of use.

I have entered into a detailed description of the construction and relative arrangement of the parts embraced in the present and preferred embodiment of my invention in order to impart an exact understanding of the said embodiment in all of its details. I do not desire however to be understood as limiting myself to the construction and relative arrangement of parts as disposed, my invention being defined by my appended claims within the scope of which structural changes or modifications may be made without departure from my invention.

Having thus described the invention, what I claim is:—

1. A micrometer attachment comprising an arm attachable to a micrometer, a second arm connected with and adjustable relative to the first arm by its engagement with a movable part of the micrometer, a movable

spring influenced member connected with the second arm and engaged with and operable by movement of said second arm, and a scale complementary to said spring influenced member.

2. A micrometer attachment comprising an arm adapted to be attached to one arm of the U-shaped portion of a micrometer, a bar fixed to and extending from said arm, a sleeve movable on said bar, means for adjustably fixing the sleeve to the bar, a member attached to and movable longitudinally of the sleeve, said member being provided with an arcuate scale, and being also provided with an arm opposite the first named arm, a pointer pivoted to said member, and a movable arm connected to the arm of said member and engaged with and adapted to operate the pointer and operable by a movable part of a micrometer.

3. A micrometer attachment comprising an arm adapted to be attached to one arm of the U-shaped portion of a micrometer, a bar fixed to and extending from said arm, a sleeve movable on said bar, means for adjustably fixing the sleeve to the bar, a member attached to and movable longitudinally of the sleeve, said member being provided with an arcuate scale, and being also provided with an arm opposite the first named arm, a pointer pivoted to said member, and a movable arm connected to the arm of said member and engaged with and adapted to operate the pointer and operable by a movable part of a micrometer; the said movable arm being apertured to receive said bar and to have sliding and pivotal movement thereon.

4. A micrometer attachment comprising an arm adapted for attachment to a portion of a micrometer, a bar fixed to and extending at right angles from the said arm, a sleeve slidable on said bar and having an apertured projection, means for adjustably fixing the sleeve to the bar, a member attached to and movable longitudinally of said sleeve, said member being equipped with an arcuate scale and being provided with an arm of resilient character opposite the first named arm, a pointer pivoted to the said member, a movable arm operable by a movable part of a micrometer and connected to the arm of said member and engaged with the said pointer, said resilient arm of the member holding said member under yielding pressure against the movable arm, a rod connected to said movable arm and extending through said apertured projection of the sleeve and having an abutment spaced from said aperture projection, and a spring mounted on said rod and interposed between the apertured projection of the sleeve and the enlargement of the rod.

5. A micrometer attachment comprising an arm equipped for attachment to a portion

of a micrometer, a bar fixed to and extending at right angles from the said arm, a sleeve slidable on said bar and having an apertured projection, means for adjustably fixing the sleeve to the said bar, a member attached to and movable longitudinally of said sleeve, said member being equipped with an arcuate scale and being provided with an arm of resilient character opposite the first named 5 arm, a pointer pivoted to the said member, a movable arm operable by a movable part of a micrometer and connected to the arm of said member and engaged with the said pointer, said resilient arm of the member 10 holding said member under yielding pressure against the movable arm, a rod connected to said movable arm and extending through said apertured projection of the sleeve and having an abutment spaced from 15 said apertured projection, and a spring mounted on said rod and interposed between the apertured projection of the sleeve and the enlargement of the rod; the said bar being grooved, and the said movable arm apertured 20 to receive the bar and provided with a 25 stud disposed in the groove of the bar.

6. A micrometer attachment comprising an arm or bracket equipped for fixture on a micrometer, a bar fixed with respect to and 30 extending from the said arm or bracket, means slidable on and capable of being adjustably fixed to the said bar and equipped with a spring pressed or influenced element operable by a movable element of the 35 micrometer; the said element being provided with a teat opposed to the movable element of the micrometer, and the said teat being in

the form of the head of a screw detachably connected to the said element.

7. A micrometer attachment comprising 40 an arm or bracket adapted to be fixed to a portion of a micrometer, a bar extending from said arm or bracket, a sleeve mounted on said bar, means for adjustably fixing said sleeve to the bar, a member attached to and 45 movable longitudinally relative to the sleeve, said member equipped with a scale, a movable pointer complementary to said scale and carried by said member, and a spring influenced element operable by a movable part of 50 a micrometer and engaged with and adapted to transmit movement to said pointer.

8. A micrometer attachment comprising 55 an arm or bracket adapted to be fixed to a portion of a micrometer, a bar extending from said arm or bracket, a sleeve mounted on said bar, means for adjustably fixing said sleeve to the bar, a member attached to and movable longitudinally relative to the sleeve, said member equipped with a scale, a movable pointer complementary to said scale and carried by said member, and a spring influenced element operable by a movable part 60 of a micrometer and engaged with and adapted to transmit movement to said 65 pointer; the said element being apertured and receiving said bar and being pivoted to and movable alongside the element carried by and movable longitudinally of the sleeve and therefore having sliding and pivotal 70 movement on the bar.

In testimony whereof I affix my signature.

ROBERT W. OLSON.
